CLAIM

The ornamental design for a camera housing, as shown and described.

DESCRIPTION

FIG. 1 is a rear, upper, right perspective view of a camera housing of our new design;

FIG. 2 is a front, lower, left view thereof;

FIG. 3 is a rear view thereof;

FIG. 4 is a front view thereof;

FIG. 5 is a left view thereof;

FIG. 6 is a right view thereof;

FIG. 7 is a top view thereof; and,

FIG. 8 is a bottom view thereof.
